Glen E. Millard, St. Paul, Minn., assignor to
Lactona Incorporated, St. Paul, Minn., a corporation of Minnesota

Application August 13, 1949, Serial No. 4,490

Term of patent 14 years

(Cl. D86—1)

To all whom it may concern:

Be it known that I, Glen E. Millard, a citizen of the United States, residing at St. Paul, county of Ramsey, and State of Minnesota, have invented a new, original, and ornamental Design for Detachable Toothpick Assembly, of which the following is a specification, reference being had to the accompanying drawing, forming part thereof.

Figure 1 is a perspective view of a detachable toothpick assembly showing my new design;

Figure 2 is an end elevation view of the same;

Figure 3 is a top plan view of the combination; and

Figure 4 is a bottom plan view of the same.

I claim:

The ornamental design for a detachable toothpick assembly, as shown.

GLEN E. MILLARD.
